UNITED STATES PATENT OFFICE

HENRY REUBEL, OF NEW YORK, N. Y., ASSIGNOR TO THE KRODER REUBEL COMPANY, INC., OF NEW YORK, N. Y., A CORPORATION OF NEW YORK

DRAPEY AND CURTAIN SUPPORT AND OPERATING MEANS THEREFOR

Application filed April 6, 1929. Serial No. 352,977.

This invention relates to drapery and curtain support and operating means therefor and more particularly of the type which embodies a hollow guide having a longitudinal slot in one face, the walls of the hollow guide or tube on opposite sides of the slot serving as tracks or bearing surfaces for the plurality of carriers which are attached to the curtain or drapery, and which have suitable 5 runners adapted to slide or roll along the tracks during the movement of the curtain or drapery. This invention relates to and is 10 an improvement upon the devices shown in my prior Patent No. 1,545,850, July 14, 1925 15 and patent to Furlong, No. 1,661,137, February 28, 1928.

An object of this invention is to provide a device or appliance of this character in 20 which the curtain or drapery may be adjusted without the jamming or clogging of the carriers in the tracks and in which the carriers will slide freely in their movements, which are controlled by cords, wires or the like connected to certain of the carriers only.

Another object of this invention is the provision of a hollow guide or tube which is shaped so as to receive and conceal the operating cords, wires and the like and in which 25 operating carriers are provided with saddle members to frictionally and adjustably receive the operating cords or wires, whereby these operating carriers may be readily adjusted upon said operating cords or wires.

Another object of this invention is the provision of removable mountings or frames 30 for the end pulleys or wheels about which the operating cords or rods run.

Further objects include improvements in 35 details of construction and arrangement whereby a simple and effective device of this character is provided.

To the accomplishment of the foregoing and such other objects as may hereinafter appear, this invention consists in the construction, combination and arrangement of parts hereinafter described and then sought 40 to be defined in the appended claims, reference being had to the accompanying drawings forming a part hereof, and which show merely for the purpose of illustrative dis-

closure a preferred embodiment of my invention, it being expressly understood, however, that various changes may be made in practice within the scope of the claims without digressing from my inventive idea.

55

In the drawings—
Figure 1 represents an elevational view of a curtain or drapery supported by a device of this character, the curtain or drapery being shown closed.

60

Figure 2 is a view similar to Figure 1, the curtain or drapery being shown open.

Figure 3 is a longitudinal vertical cross section through a device constructed to embody my invention.

65

Figure 4 is a bottom plan view of the device shown in Figure 3.

Figure 5 is a vertical cross section taken substantially on line 5—5 of Figures 3 and 4.

70

Figure 6 is a vertical cross section taken substantially on line 6—6 of Figures 3 and 4.

Figure 7 is a vertical cross section taken substantially on line 7—7 of Figures 3 and 4.

Figure 8 is a detail perspective view of one of the operating carriers.

75

Figure 9 is a detail perspective view of the frame or mounting for one of the pulley constructions.

Figure 10 is a perspective view of the frame or mounting for the other pulley construction.

80

Referring now to the drawings, the numeral 1 designates a hollow guide which is adapted to be suitably secured to any suitable support. This guide is provided with a longitudinal slot or opening 2. The walls at each side of said slot or opening are curved as at 3 to provide a pair of tracks or bearing surfaces 4 extending longitudinally of the guide. These curved portions are substantially semi-circular in extent and merge into an upwardly extending wall 5, which provides an enlarged space 6 which is adapted to receive the operating cords, wires, etc., hereinafter referred to.

85

The carriers are designated generally by the reference character 7 and are preferably of the form shown in Reubel Patent No. 1,545,850, though they may be of the form shown in the Furlong Patent No. 1,661,137 or

90

of other constructions. Essentially, however, they include, referring to Figures 6 and 8 particularly, a body member 8 having an axle or shaft 9 extending eccentrically therethrough. On this shaft on opposite sides of the body member are mounted suitable rollers or wheels 10 which are adapted to bear upon the bearing surfaces and run along the tracks, as clearly shown in Figure 6. These wheels or rollers are preferably spaced from the body member by means of the washers 11. The body member is of substantial thickness axially so as to substantially fill the slot 2 in the tubular or hollow guide 1. This body member is of substantial thickness diametrically and is greater in that dimension than the diametrical thickness of the wheels or rollers 10 so as to prevent the wheels or rollers of adjacent carriers jamming together in operation. This is all shown and described in the previous patents above referred to. The body member is provided with suitable eyes or other attaching means 12 which are preferably swivelled thereto. These eyes are designed to be attached or secured to the curtain, drapery and the like.

Certain of the carriers 7 must be positively connected to the operating wire or cord 13 and this is accomplished by providing the saddle member 14 (see Figure 8), which has an elongated and substantially flat body portion 15, provided with an aperture 16 near each end. This body portion 15 has a downwardly turned ear or lug 17 provided on each side and spaced so as to overlap or overhang the body member 8 of the carrier. These ears or lugs 17 are apertured to receive the axle or shaft 9 of the carrier. The operating cord, wire or the like 13 is passed through the two openings or apertures 16 and drawn tight therein whereby that particular carrier is frictionally attached to the operating wire, cord or the like. This frictional attachment is of sufficient security to enable the wire, cord and the like to be pulled to move the carrier so as to adjust the curtain, drapery and the like. However, the frictional engagement does not prevent a ready adjustment of that carrier upon the operating cord, wire and the like. Preferably the two middle carriers are provided with these attaching means and are connected to the operating cord or wire and the other carriers are merely loose or idle in the hollow tube or track and connected to the curtain, drapery and the like, and are pushed by the middle carriers when moving in one direction and pulled by the curtain, drapery and the like when the movement is in the other direction. I apply the term "operating carriers" to these middle carriers.

The wire or cord 13 passes through the hollow tube or track in two lays having free ends 18 and 19. At one end of the track I provide a single pulley or wheel 20 mounted

upon a vertical axis and at the other end of the hollow tube or track I provide a pair of pulleys 21 mounted upon a horizontal axis. The cord or wire 13 is looped around the pulley 20 and the free end portions 18 and 19 are then passed over the pulleys 21. Intermediate the pulley 20 and pulleys 21 each lay of the cord or wire is connected to one of the saddle members 14 so that as one of the free ends is pulled, the carriers with the saddle members will be moved in one direction, as for instance to open the curtain, drapery and the like, and when the other free end of the cord or wire is pulled, these carrier members will be moved in the opposite direction, as for instance to close the curtain, drapery or the like.

I have provided a new means for mounting and assembling the pulleys 20 and 21. Referring to Figure 10 first, which shows the removable mounting for the pulley 20, it is to be seen that that includes the bottom member 22 having side flanges 23 which are shaped so as to fit within the semi-circular curved portions 3 of the hollow tube or track member. This part is also provided with a vertical end flange 24 from which extends an upper lug 25. The lower lug 26 is struck up from the bottom and arranged in spaced relation to the lug 25, being apertured to receive the stud or shaft 27 upon which pulley 20 is mounted for rotation. The lug 25 is shaped to fit within the longitudinal recess portion 6 and the end flange 24 is shaped to close the end of the hollow tube or track member.

Referring now to Figure 9, the removable mounting for the pulleys 21 comprises the base or bottom member 28 having the side flanges 29 which are adapted to fit the semi-circular portions 3 of the hollow tube or track member. This element is in turn provided with the end flange 30 from which extends a pair of spaced lugs or projections 31, which are apertured to receive a horizontal stud or shaft 32, upon which the pulleys 21 are mounted for rotation. A suitable spacing element or partition 33 is positioned in this mounting between the pulleys 21 so as to prevent the lays of the cord or wire becoming entangled. The lugs or projections 31 are arranged so as to fit tightly within the vertical portions 5 of the hollow track or tube member and the end flange 30 has a reduced projection 34 which is adapted to fit against the end of the hollow track or tube.

It is to be noted that the extra space 6 afforded by the particular track or tube construction receives the pulleys and the cords and also the saddles for the operating carriers, as well as the removable end pieces and mountings for the two pulley constructions.

What I claim is:—

1. A drapery and curtain support including, in combination, a hollow guide having a

longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, said hollow guide being formed so as to provide an enlarged longitudinal space in its upper portion, flexible operating means connected to certain of said carriers and extending from one end of the hollow guide to the other within said enlarged longitudinal space, a removable pulley mounting and support frictionally held within each end of said hollow guide.

2. A drapery and curtain support including, in combination, a hollow guide having a longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, said hollow guide being formed so as to provide an enlarged longitudinal space in its upper portion, flexible operating means connected to certain of said carriers and extending from one end of the hollow guide to the other within said enlarged longitudinal space, a removable pulley mounting and support frictionally held within each end of said hollow guide, having a base portion, side flanges frictionally engaging the side walls of the hollow guide and end flanges engaging the ends of said hollow guide.

3. A drapery and curtain support including, in combination, a hollow guide having a longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, said hollow guide being formed so as to provide an enlarged longitudinal space in its upper portion, flexible operating means connected to certain of said carriers and extending from one end of the hollow guide to the other within said enlarged longitudinal space, a removable pulley mounting and support frictionally held within each end of said hollow guide, having parallel lugs, shafts supported by said parallel lugs and pulleys mounted on said shafts.

4. A drapery and curtain support including, in combination, a hollow guide having a longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, said hollow guide being formed so as to provide an enlarged lon-

gitudinal space in its upper portion, flexible operating means connected to certain of said carriers and extending from one end of the hollow guide to the other within said enlarged longitudinal space, a removable pulley mounting and support frictionally held within each end of said hollow guide, having parallel lugs, shafts supported by said parallel lugs and pulleys mounted on said shafts, a pulley in one mounting being arranged on a vertical axis and the pulleys in the other mounting being arranged on a horizontal axis.

5. In combination with a hollow tube or guide for a drapery and curtain support, carriers mounted to move therein, flexible means for operating said carriers and removable end members for said hollow guide, each end member constituting a support for a pulley for said flexible means and having side flanges frictionally engaging the sides of said hollow guide and an end flange closing the end of said hollow guide and parallel lugs, a shaft journalled in each of said parallel lugs and a pulley mounted upon each shaft.

6. A drapery and curtain support including, in combination, a hollow guide having a longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, flexible means for operating said carriers, means for attaching said flexible means to certain of said carriers including a saddle member pivotally mounted upon said carrier and having a plurality of apertures to receive said flexible means.

7. A drapery and curtain support including, in combination, a hollow guide having a longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, flexible means for operating said carriers, means for attaching said flexible means to certain of said carriers including a saddle member pivotally mounted upon said carrier, and having an elongated body portion provided with an aperture near each end through which said flexible means is passed whereby a frictional and adjustable connection between said saddle member and said flexible means is provided.

8. A drapery and curtain support including, in combination, a hollow guide having a longitudinal slot therein, the walls of said guide on opposite sides of said slot constituting tracks extending lengthwise of the guide, a plurality of carriers, each carrier including runners adapted to run on said tracks, said carriers having a drapery-attaching member secured thereto, said hollow guide being formed so as to provide an enlarged lon-

member secured thereto, flexible means for operating said carriers, means for attaching said flexible means to certain of said carriers including a saddle member pivotally mounted upon said carrier, having a flat body portion provided with restricted apertures near each end of a size sufficient to receive said flexible means and at the same time to cause an abrupt bending of the same whereby said flexible means is frictionally and adjustably connected to said saddle member.

9. As an article of manufacture, a carrier for a curtain and drapery support including a body member, an axle extending through said body member and provided with a bearing member on each side thereof, a saddle member provided with lugs adapted to embrace said body member and to receive said axle, said saddle member also having an elongated body member provided with openings near each end to receive a flexible operating means.

10. As an article of manufacture, a carrier for a curtain and drapery support including a body member, an axle extending through said body member and provided with a bearing member on each side thereof, a saddle member provided with lugs adapted to embrace said body member and to receive said axle, said saddle member also having a substantially flat body member with a restricted aperture near each end thereof adapted to receive and sharply bend a flexible operating means.

11. A drapery and curtain support including, in combination, a hollow guide for the curtain or drapery supporting means, a removable end member for each end of said hollow guide, each removable end member being provided with bottom and side flanges adapted to frictionally engage the bottom and sides of the hollow guide, and also having a pulley rotatably mounted therein.

12. A drapery and curtain support including, in combination, a hollow guide for the curtain or drapery supporting means, a removable end member for each end of said hollow guide, each removable end member being provided with bottom and side flanges adapted to frictionally engage the bottom and sides of the hollow guide, each removable end member being formed with parallel lugs, an axle mounted in said parallel lugs and a pulley rotatably mounted on said axle.

13. In a drapery and curtain support, a hollow guide member formed with a longitudinal slot, semi-circular side portions at each side of said slot merging into vertical portions which are connected to a flat top portion forming an enlarged longitudinal space in the upper portion of said hollow guide member which space has a width substantially equal to the combined width of the rollers for the flexible means.

14. In a drapery and curtain support, a

hollow guide member formed with a longitudinal slot, semi-circular side portions at each side of said slot merging into vertical portions which are connected to a flat top portion forming an enlarged longitudinal space in the upper portion of said hollow guide member, and removable end members provided with rollers and having bottom and side flanges adapted to frictionally engage portions of the hollow guide member which enlarged longitudinal space has a width substantially equal to the combined width of the rollers.

15. In combination in a drapery and curtain support, a guide for the curtain or drapery supporting means, a removable end member for the end of said guide, said removable end member being provided with top, bottom and side flanges adapted to frictionally engage the top, bottom and sides of the guide and also having means mounted therein for guiding and supporting a flexible curtain operating means.

16. In combination in a drapery and curtain support, a guide for the curtain or drapery supporting means, a removable end member for the end of said guide, said removable end member being provided with bottom and side flanges adapted to frictionally engage the bottom and sides of the guide, said end member also being provided with a flange adapted to abut and close the end of the guide, and means mounted in said end member for guiding and supporting a flexible curtain operating means.

17. A removable end member adapted to be received within a guide and adapted to be removed therefrom after the guide is fastened to a structure for use, said end member being provided with top, bottom and side flanges adapted to frictionally engage the top, bottom and sides of the guide and also having means for guiding and supporting a flexible curtain operating means.

18. A removable end member adapted to be received within a guide and adapted to be removed therefrom after the guide is fastened to a structure for use, said end member being provided with bottom and side flanges adapted to frictionally engage bottom and sides of the guide, said end member also being provided with a flange adapted to abut and close the end of the tube or guide and means mounted in said end member for guiding and supporting a flexible curtain operating means.

19. A device of the character described, comprising a removable end member having a base and adapted to be received within a guide, said end member being provided with an end flange adapted to abut the end of the guide and parallel lugs on said end member for receiving a pulley, one of said lugs being struck up from said base.

20. As an article of manufacture, a carrier

for a curtain and drapery support, including, a body member, an axle extending eccentrically through said body member and provided with bearing members, a saddle member provided with lugs adapted to embrace said body member and to receive said axle and be pivoted thereon, said saddle member also having an elongated body member provided with openings adjacent each end to receive a flexible operating means.

21. As an article of manufacture, a carrier for a curtain and drapery support, including, a body member, a saddle member provided with lugs adapted to embrace said body member, means for pivotally mounting said saddle member on said body member, said saddle member having an elongated body provided with openings adjacent each end to receive a flexible operating means, and a drapery attaching member swivelly connected to said body member.

In testimony that I claim the foregoing, I have hereunto set my hand this 2nd day of April, 1929.
